UNITED STATES PATENT OFFICE

WILLIAM DUBILIER, OF NEW YORK, N. Y., ASSIGNOR TO DUBILIER CONDENSER CORPORATION, OF NEW YORK, N. Y., A CORPORATION OF DELAWARE

VARIABLE CONDENSER

Application filed May 12, 1925. Serial No. 29,783.

This invention relates to an improved electrical condenser; especially a condenser designed for convenient variation of electrostatic capacity.

The general object of the invention is to provide a variable condenser which can be cheaply manufactured in large quantities; which comprises few parts that can be easily and quickly assembled; which can operate efficiently and accurately; and which is capable of giving long service without derangement of either structure or function.

In practice, the condenser according to this invention is very simple in form and is intended for use in connection with radio circuits, although it is also adapted for other purposes as well.

The nature and scope of the invention will appear fully from the following description taken with the accompanying drawing which present several forms in which my invention can be embodied; but this disclosure is illustrative only and I may vary the shape, size and relative arrangement of the parts constituting the condenser and still keep within the principle which controls my invention; and the claims appended hereto are to be construed accordingly in view of the broad terms in which same are expressed.

On the drawings:

Figure 1 is an end view of one form of condenser according to my invention;

Figure 2 is a bottom plan thereof shown as if the observer were looking up underneath the condenser appearing in Figure 1, partly in section;

Figure 3 is a side view seen from the right of Figure 1, of said condenser;

Figure 4 is an end view of another form of condenser according to my invention;

Figure 5 is a bottom plan of the condenser shown in Figure 4, partly in section;

Figure 6 is a view of the opposite end of the condenser of Figures 4 and 5, presented as if viewed from the bottom of Figure 5;

Figure 7 shows a detail of the construction of this second form of my improved condenser;

Figure 8 is an end view of a third form of condenser according to my invention;

Figure 9 is a bottom view of the condenser shown in Figure 8, partly in section;

Figure 10 is a plan view partly in section of a fourth form of my improved condenser;

Figure 11 is an end view of a fifth form 55 of a condenser according to my invention, somewhat similar to Figure 8;

Figure 12 is a bottom view of the condenser of Figure 11;

Figures 13 and 14 are plan views, partly 60 in section, of additional modifications of my improved condenser; and

Figures 15 and 16 are respectively, a plan and an end or side view of a still further modification of my improved condenser. 65

The same numerals identify the same parts throughout.

Referring first to Figures 1, 2 and 3, I use the numeral 1 to indicate a fixed electrostatic member or stator comprising a curved or 70 semi-cylindrical plate 1, and the numeral 2 to indicate a movable electrostatic member or rotor comprising a similar curved plate; these two plates being parallel to each other. The stator also includes a number of parallel 75 electrostatic elements, in the form of cylindrically curved ridges, ribs or projections 3, separated by intervening deep grooves or recesses 4; and the rotor further comprises similar cylindrical projections 5 separated 80 by intervening grooves 6. When the condenser is assembled, the semi-cylindrical projections 5 of the rotor will enter the recesses 4 of the stator, and the projections 3 of the stator will enter the recesses 6 of the rotor; 85 as plainly appears in Figure 2; but the projections 3 and 5 will no where make electrical contact with each other. When seen in end elevation, the rotor and stator will each appear like a comb with teeth, as indicated in Figure 2.

To hold the rotor and stator in the desired relation, the curved plate or base carrying the elements 3, is provided with radial ribs 7, which fit against a body of insulation 8 which is held to the stator by means of fastening devices or screws 9. The insulation 8 has a central opening in which is molded a metal punching to form a bearing 10 in which turns an operating shaft 11. This 100

shaft has a turned down end 12 to receive the hub 13 of the rotor 2, this hub being connected to the rotor by means of radiating ribs 14. The curved plates included in the 5 rotor and stator are really arc-shaped with concentric circular edges to make the rotor and stator, to some extent, open in the middle, and the insulation 8 is provided with a post 15 which extends through the rotor and 10 stator within the compass of the elements 3 and 5 and adjacent the shaft 11. Fixed to the end of the projection 15 is a rigid arm 16, held in place by fastening devices or screws 9, this arm extending laterally over 15 the end 12 of the shaft 11 and carrying a pointed screw 17 which enters the extremity of the reduced portion 12 of the shaft, to support said extremity and to prevent axial movement of the shaft 11 with the stator 1. 20 The hub 13 can be made rigid with the shaft 11 on the portion 12 in any feasible manner, and when the screw 17 is adjusted, the shaft 11 is forced to bring the end of the hub 13 in contact with the bearing 10. Then the 25 elements 5 will enter the grooves 6 between the elements 3 and yet be out of contact with the stator 1 at all points. On the pointed screw 17 is a lock nut 18 to hold the screw in said position. 30 The projecting elements 4 and 5 extend at right angles to the arc-shaped plates of the stator 1 and rotor 2, and they may be molded or cast into these plates, or the plates may be cut to provide slots to receive them. As 35 already mentioned, these elements 3 and 5 are semi-cylindrical, that is to say, they are all curved on the arcs of concentric circles which have the axis of the shaft 11 as a center, and each may be 180 degrees more or less in an- 40 gular extent. The insulation 8 may be bakelite, and is offset or spaced axially along the shaft 11 from the rotor and stator to some extent, in order to reduce the losses in the operation of the condenser. From the insulation 8 extends two bosses 19 having screw holes 20, to enable the condenser to be mounted upon a suitable support or panel. 45 In Figures 4, 5 and 6, the stator is indicated at 1' and the rotor at 2'. Each is provided with substantially semi-cylindrical projections 3 and 5 as before, with intervening grooves or recesses 4 and 6, and the flat or plane part of the rotor and stator which are normal to the axis of the shaft, instead 55 of being arc-shaped plates, are here given the form of semi-circular discs. From the center of the stator projects a hub or boss to provide a bearing 10' to receive the shaft 11'. This shaft 11' has a peripheral groove 21 ad- 60 jacent the outside surface of the stator, and in this groove is disposed a locking ring 22. The purpose of this locking ring is to engage a flat slightly concave spring disc 23, having radial cuts or recesses 24. This disc 65 is perforated in the middle to be slipped upon the shaft against the flat outer face of the stator before the locking ring 21 is put into the groove 22, and this ring compresses the spring disc against the stator, for a purpose which is stated below. The stator carries a 70 projection 25 having a threaded opening to receive a binding screw 9 to enable a conductor to be attached thereto. 75 The portion of the rotor 2' which is normal to the shaft 11' is dished somewhat as shown at 26 and has a central member 27 from the inner surface of which project in a radial direction, a flange or collar 28 at the inner edge of which are projections 29 adapted to serve as rivets. These portions 29 extend in the same 80 direction as the axis of the rotor 2, and they act to hold in place two discs of insulation 30 and 31. The projections 29 may be in any number, and they extend in both directions axially of the condenser. Preferably, they 85 are arranged in pairs, one of each pair extending towards the stator and the other in the opposite direction. The discs 30 and 31 are perforated near the circumference to enable the ends of the portions 29 to be passed 90 through them, and the ends of these portions when expanded by pressure, will secure these discs in the manner of rivets to the rotor 2'. When secured, the discs 30 and 31 will have the collar 28 between them as indicated in 95 Figure 5. These discs have central openings to receive a hub or sleeve 32 having a collar 33 at one end against which the inner disc 30 abuts. This hub is also encircled by a spacing ring or washer 34 between the discs 30 and 31, and a small ring or washer 35 is placed 100 against the face of the outer disc 31, the outer end of the hub 32 passing through this ring 35 and being expanded by pressure, to hold the hub 32 on same. In practice, the rotor 2' 105 is assembled with the discs 30 and 31, and the sleeve 32, and the ends of the rivets 29 and of the sleeve 32 are expanded to secure the hub 32, the discs 30 and 31, and the stator together. Then the rotor 2' can easily be mounted upon 110 the shaft 11' by slipping the hub over the end of the shaft 11' until it abuts a shoulder 36 which will be at the inner end of the bearing 10'. The outer extremity of the shaft 11' will then be expanded the same as the adjacent end of the sleeve 32 and thus the rotor 2' and the shaft 11' will be secured together. 115 The location of the locking ring 21 will be such that while it keeps the spring disc 23 pressed against the flat part of the stator 1', this spring will so act upon the shaft 11 as to move it axially as far as the end flange or collar 33 on the sleeve 32 will permit. That is to say, the sleeve 32 will be held against the inner end of the bearing 10', and the rotor 2' 120 thus be maintained in the proper position to keep the electrical elements or projections 5 which it carries, in correct relation to the stator 1', that is, with the elements 5 the 125 130

proper distance at all points from the elements 3.

The rotor 2' is provided with a flange 37 that is milled along the edge thereof, and is fixed to the straight edge of the portion of the stator 1' which is perpendicular to the stator 1', is a piece of insulation 38 on which is fastened a contact strip 39. From this contact strip runs a piece of insulated wire 40 to one 10 of the rivets 29 to make connection to the stator 1'.

The stator 1' also carries a vernier adjusting device comprising a rotatable stem 41 which extends through bearing apertures in 15 radial projections 42. This stem has a shoulder 43 which is flush with the lower face of the upper projection 42 in Figure 5, and between the projections, and encircling the stem 41, so as to engage the shoulder 43, 20 is a coil compression spring 44. Beyond the other projection 42, the stem 41 carries a fibre friction wheel 45 which fits against the shoulder 46 near the extremity of the stem, and is held in place by riveting over the 25 extremity of the stem 41, as indicated at 47. Both the wheel 45 and the milled flange 37 are coned to a slight extent, and the spring 44 acts to keep the stem 41 retracted, and the wheel 45 out of engagement with the rotor 2'. 30 When one wishes to use this vernier attachment, he pushes the stem 41 to bring the wheel 45 against the flange 37, and then turns the stem 41 to give the minute adjustment of the rotor desired.

In both forms of condenser thus far described, it is seen that the adjustment is made by turning the shaft carrying the rotor, so as to cause a larger or smaller portion of the outside surfaces of the elements or armatures 3 and 5 to be in juxtaposition with each other. Both the rotor and the stator have portions which are perpendicular to the operating shafts, to serve as a base on which the elements 3 and 5 are mounted. The elements 3 and 5 do 40 not have their opposite faces parallel, but they are rather tapered. That is to say, the opposite faces of each substantially semi-cylindrical element 3 or 5 converge towards the outer edges of these elements; and this construction is made so that when the stator and rotor are case, they cannot only be withdrawn easily, from the molds; but also they combine the greatest possible strength with the greatest possible thinness, and not only is material 50 saved, but bending of the plates out of proper position is prevented.

In the form shown in Figures 1, 2 and 3, the stator is insulated from the shaft, and the rotor and shaft are electrically connected. 60 The range of adjustment is about 180 degrees, and the post 15 will act as a stop for the rotor in the position of both maximum and minimum capacity.

In the form of condenser shown in Figures 65 4, 5 and 6, the piece of insulation 38 acts as

a stop for the rotor in the position of both maximum and minimum capacity, and the range of rotation is about one-half circle, as before. In this type of condenser, the stator and the shaft 11' are in electrical connection, so that they can be of the same potential; while the rotor is insulated from the shaft and the amount of insulation is actually very small. The amount of taper which is given to the armatures 3 and 5 will be 75 more than one degree.

In these two forms of condensers, it is desirable that the elements 3 and 5 be secured to the plates or portions normal to the operating shaft of the rotor and stator, because 80 these plates or portions serve as bases or heads, and the armatures 3 and 5 with these heads or bases can either be cast in one piece, or the armatures can be rolled or punched, and afterwards attached to these heads or 85 bases at right angles to the surface thereof, and in proper position with respect to the axis of the operating shaft.

In the form of my condenser shown in Figures 8 and 9, the stator 1^a comprises radiating arms 7' that are preferably of metal made fast to a head of insulation 8' by means of screws 9', washers 48 being interposed between these arms 7' and the insulation 8'. The arms 7' on one side are slotted to receive semi-cylindrical elements or armatures 3', the edges of which cut into the slots and these elements may be made fast by being cast with the arms 7', or otherwise. The rotor 2^a is preferably in the form of a semi-circular disc bearing substantially semi-cylindrical armatures or elements 5' which enter spaces between the elements 3'. From the center of the semi-circular head or plate of the rotor 2^a, projects a journal or shaft 49 which may be cast in one piece with the rotor or otherwise secured thereto, and this shaft has a sloping or conical shoulder 50 to receive a bushing 51, with a counterbored end to fit the shoulder 50. The opposite end of this bushing is also counterbored to receive a washer 52 having a coned face, and on this washer is a perforated spring disc 53. Adjacent the washer 52, the shaft is threaded to receive a couple of lock nuts 54 which press down upon the spring disc 53. When these lock nuts are turned up, they hold the sleeve or bearing 51 snugly between the washer 52 and the shoulder 50, and as this sleeve 51 is made fast inside of a hub or boss 10^a of the insulation 8', the heads of the rotor and stator are held the required distance apart.

In Figure 10, the stator 1, the rotor 2 and the armatures 3 and 5 with the grooves 4 and 6, are shaped substantially the same as in the case of the condenser shown in Figures 1, 2 and 3; except that the stator has no ribs 7, but is made fast to the insulating head 8' by fastening devices 9' and washers 48, the 125

same as in the condenser shown in Figures 8 and 9. Figure 10 shows the rotor having the shaft 11^a projecting from the middle of same and otherwise the construction and manner of mounting the shaft 11^a to turn with the stator in the insulation 8', is the same as in Figures 8 and 9.

In Figures 4 to 10 inclusive, the bosses 19 with screw threaded holes 20 are also shown 10 for mounting the condensers on a panel.

In Figures 11 and 12, the form there shown comprises a stator 1^b which includes a substantially semi-circular plate of conductive material bearing substantially semi-cylindrical elements or armatures 3'. The rotor 2^b likewise embraces a substantially semi-circular plate or head from the face of which projects substantially semi-cylindrical elements or armatures 5', the armatures of each 15 set projecting into the spaces of the other set. From the inner face of the head of the stator, projects a bearing 10^b in which is mounted the shaft 11'. This shaft like the condenser of Figure 5 has a groove 21 with 20 a locking ring 22, and a spring disc 23 on the shaft abutting the ring 22, and the stator 1^b. In the head of the rotor is a bearing 27^b which is filled with insulation 30^a molded or otherwise secured in this bearing and carrying 25 in its middle, a sleeve or hub 32' which is slipped upon the end of the shaft 11' as a journal, and has a collar 33' at one end, while over the shaft is passed a washer 35 held in place by a lock nut 55 and pressed 30 against the insulation 30^a, and the opposite end of the sleeve 32'. Normally, the sleeve 32' will abut both the bearing 10^b and a shoulder 36 on the shaft 11'.

In this form of condenser as that shown in 40 Figures 4, 5 and 6, the elements 3 and 5 may either be cast in the heads of the rotor and stator, or they may be rolled or punched and inserted into slots cut in the opposing faces of the rotor and stator.

45 Figure 13 shows a further modification in which the stator 1^b is in two parts, each comprising a head or plate from the one face of which projects elements 3, the opposite faces of which converge as in Figures 2, 5 and 10, 50 the elements 3 being separated by grooves or recesses 4, and the two heads are connected by a cylindrical casing 56, held to the rims of the two heads by screws 9. The rotor is disposed inside of the casing and it comprises 55 a head or plate with armatures or elements 5 on both faces, separated by grooves or recesses 6. The elements 5 on both faces of the rotor which are located at the same radial distance from the axis of rotation, are in line 60 with each other, so that the elements 5 all can project into the spaces 4 of the stator. One of the stator heads has a central bearing 10^b in which is a bushing or jacket 57, receiving a shaft 11^b, the outer end of the jacket 65 being flanged at 58, and the inner end being

threaded at 59 to receive a nut 60. The head of the rotor has a central bearing opening 27^b in which is secured insulation, the same as described in connection with Figures 11 and 12, and at the middle of the insulation is a hub or sleeve 35 having a flange or collar 33', at one end, and encircled at the other end, by a washer 35 secured against the face of the insulation 30^a by riveting over or expanding the adjacent end of the hub 32'. This hub 70 is slipped on the reduced end of the shaft 11^b, and abuts a shoulder 36 adjacent the inner end of the shaft 11^b, and adjacent the inner end of the bushing 57. The other stator head has a threaded opening to receive 80 an adjustable pointed screw 17, carrying a lock nut 18, the point of this screw engaging the inner end of the shaft 11^b, both to support the inner end and to hold it in proper axial position. Obviously, if the hub 32' is made 85 fast on the reduced extremity of the shaft 11^b in front of the shoulder 36, and if the shaft will hold the stator in proper position, so that the elements 5 will not make contact with the elements 3, with the sleeve 32' abutting the inner end of the bushing 57, the screw 17 can be adjusted to prevent movement of the stator in the opposite axial direction and thus prevent movement of the stator 90 which might bring about contact between the armatures 5, and the elements 3 of the other stator head carrying the screw 17.

Figure 14 shows a variable condenser with a two part stator 1^c, each stator head having armatures 3^c separated by recesses 4^c, and the rotor 2^c carries armatures 5^c, separated by recesses 6^c, which are staggered on the two sides of the rotor; that is, the armatures on one side of the rotor are not in alinement each to each with the armatures on the other side, and the armatures 3^c of the stator are correspondingly arranged. The two heads of the stator may be mounted in any suitable manner in fixed position by means of projections 19, as shown in the other views, or otherwise. At the centers of the two parts of the stator are inset pieces of insulation 30^c, one of which carries a pointed regulating screw 17 with a lock nut 18 to engage the inner end of the shaft 11'. The stator is 100 fixed to the shaft, and has a central hub 61 disposed against a shoulder 36 of the shaft 11'. The other stator carries in the middle of the insulation 30^c, a bearing 57' having a flange 58 and carrying on its opposite end a nut 59, this bearing being rigid in the stator head carrying it, and the shaft 11' passing through this bearing. In this condenser, 110 there is no outside casing 56.

115 In Figures 15 and 16, I show a condenser comprising a shaft 11 passing through a central bearing 10 of a metallic stator comprising a head having armatures 3, separated by recesses 4, but arranged in three groups or sections. The ends of the armatures of each 120

section are separated by flat sector-shaped spaces on the head of the stator as indicated in Figure 15. Hence, the separate groups of armatures 3 are really sector shaped also, that is, if radial lines were drawn from the center of the stator along the ends of the armatures of each group, a sector of a circle would be enclosed. Hence, the armatures are not substantially semi-cylindrical, although they are cylindrically curved; but are less than a semi-cylinder in circumference. The rotor 2^d comprises a plate or head of insulation perforated at the middle and carrying a hub or sleeve 32' having a collar 33' engaging one face of the stator, so that the stator can be mounted on the reduced end of the shaft 11 and abut a shoulder 36. The stator is retained on the shaft by a washer 35 and a nut 55. This rotor comprises armatures 5, separated by recesses 6 in three groups arranged as described in connection with the stator; and the armatures of each group for the rotor may be formed by casting, machining, or otherwise, as separate units, each consisting of a plate or head 62 from one face of which the armatures project, the heads being secured to the head of the rotor 2^d by screws 9. The head of the stator can be mounted on a panel in fixed position by means of projections 19 having screw holes 20, as employed above in connection with all the other views.

When the condenser of Figures 15 and 16 is adjusted so that the armatures of the rotor will lie in the sector-shaped spaces between the ends of the armatures of the stator, the capacity will be a minimum, and when the rotor is turned to move its armatures into the spaces 4, so that the ends of the armatures of each group of the rotor coincide with the ends of the armatures of each group on the stator, the capacity will be a maximum.

Referring again to Figure 5, the stator is shown as provided with a projection 10" from the bearing 10', to give added support to the piece of insulation 38.

For purposes of adjustment, the range of the capacity of the various forms of condensers shown herein can be regulated by the use of shims, which can be placed, for example, between the bushing 10 and the hub 13 in Figure 1, to determine the spaces between the armatures 3 and 5. Such shims can also be used at the ends of the bearing 10' in Figure 5; in the same position between the bearings 10^b and the sleeves 32' in Figures 12 and 13; between the bushing 51 and the conical shoulder 50 in Figures 9 and 10; between the hub 61 and the bearing 58 in Figure 14; and between the head of the rotor 2^d and the head 62 of each unitary group of armatures 5 in Figure 16. Such shims are, in fact, shown at 63, and the number can be varied as desired. Such shims are also shown

at 63, between the hub 32' and bearing 10' in Figure 16.

Having described my invention, what I believe to be new and desire to secure and protect by Letters Patent of the United States is:—

1. A condenser comprising a stator having a head from one face of which semi-cylindrical armatures project, said armatures being separated by recesses, a rotor comprising a similar head from the face of which substantially similar armatures project into the recesses of the armatures on the stator, the stator having a central bearing, a shaft extending through said bearing, the rotor having a central opening with an inside collar, projections extending in opposite directions disposed at points around the inner edge of the collar, discs of insulation on both sides of said collar receiving said projections, and held in place thereby, a hub having a flange at one end passing through said discs, a washer on said hub between the said discs, and a washer on the other end of said hub and secured by the expanded end of said hub against the face of the adjacent disc, said shaft having a reduced end with a shoulder upon which said hub is secured, a piece of insulation secured on the stator, a contact piece on said piece of insulation, and a flexible insulated conductor connecting the said contact piece to said rotor.

2. A condenser comprising a rotor in the form of a metal head having substantially semi-cylindrical armatures projecting from one face, secured along their edges, to the head, and separated by intervening recesses, said head having a central bearing projecting therefrom, a rotor comprising a head having similar armatures projecting from one face thereof, and into the recesses between the armatures of the stator, the middle of said head having a bearing opening, insulation secured in the bearing opening, a central sleeve mounted in said insulation and secured therein to be disposed on the end of the shaft, and engage a shoulder thereon adjacent the end of said bearing, and a spring disc engaging the shaft to cause said sleeve to abut said bearing.

3. A condenser comprising a fixed member and a movable member, each member having a head with cylindrically curved armatures separated by recesses projecting therefrom, the armatures of one member extending into the recesses of the remaining member, and means comprising shims for adjusting the extent to which the armatures of one head project into the recesses of the other.

4. A variable condenser comprising a stator, a bearing in the stator, a rotor having a shaft in the bearing, a supporting member in said rotor, and insulation in said last named member between the shaft and the

rotor, said insulation being in the form of discs riveted to said member.

5. A variable condenser comprising a stator, a bearing in the stator, a rotor having a shaft in the bearing, a supporting member in said rotor, and insulation in said last named member between the shaft and the rotor, said insulation carrying a central hub for receiving said shaft.

10 In testimony whereof I affix my signature.
WILLIAM DUBILIER.
